UNITED STATES PATENT OFFICE

S. LEE TIBBALS, OF OSAKIS, MINNESOTA.

IMPROVEMENT IN SAW-GUMMERS.

Specification forming part of Letters Patent No. **158,756**, dated January 12, 1875; application filed October 3, 1874.

To all whom it may concern:

Be it known that I, S. LEE TIBBALS, of OSAKIS, in the county of Douglas and State of Minnesota, have invented a new and useful Improvement in Gummers, of which the following is a specification:

The invention will first be fully described, and then pointed out in the claim.

In the accompanying drawing, Figure 1 is a side view of the machine, shown partly in section. Fig. 2 is a top view.

Similar letters of reference indicate corresponding parts.

A is the bed-piece. B is the presser-bar, which is attached to the bed by a bolt, C. D is the cutter. F is the cam-lever, and G the face, of the bed or the die. The central portion of the bed is enlarged, or made strong and heavy, to enable it to stand the strain upon it. The cutter or punch D corresponds with the die in shape, and is made tapering from the cutting end. When placed on the saw, as seen in Fig. 1, it is given a smart blow with a hammer to drive it through the saw. The presser-bar B is made with a spring at the attached end, as seen at H, so that it will raise itself from the die. The presser-bar is

perforated to receive the punch. I is a perforated guide, which is attached to the presser-bar.

The saw is placed on the face of the bed or die, as represented in the drawing, and the bar is brought down onto it and held in position by the cam-lever F. This cam-lever is provided with journals, and engages with the slotted hook K, within which the end of the bar works. This slotted hook is made a portion of, or is attached to, the bed-piece A.

L is a handle on the end of the presser-bar. The die and cutter, or punch, may be made in any form, or to suit any kind of saw, and the die may be made removable from the bed, so as to be changed as occasion may require.

Having thus described my invention, I claim as new and desire to secure by Letters Patent—

The presser-bar B, having guide I and elastic portion H, combined with bed A, having die and punch D, as and for the purpose specified.

S. LEE TIBBALS.
